TYPEWRITER DEVICE FOR REPETITIVELY
OPERATING A TYPEWRITER KEY

Douglas H. Ward, Woodside, N. Y.

Application March 29, 1946, Serial No. 658,194

7 Claims. (Cl. 197—113)

(Granted under the act of March 3, 1883, as
amended April 30, 1928; 370 O. G. 757)**1**

This invention relates in general to a typewriter accessory and in particular to apparatus and means for repetitively operating a typewriter key with a single stroke.

The device is arranged for automatic operation of selected keys of a typewriter, such as the dash key, and the dash underlining key for a predetermined number of strokes, up to and including the total number of strokes permitted by the full travel of the typewriter carriage, thereby permitting a typist (1) quickly and easily to prepare numbers, letters or words in tabular form, the letters, etc., being separated from each other by these typed lines; (2) quickly and easily to underline extensive lines of typing; and (3) quickly and easily to type continuous lines of type such as the period, dash or other symbol.

The device can be attached to practically any make of manually operated typewriter; however, it can be bodily incorporated into a typewriter by a manufacturer.

It is an object of this invention to provide apparatus for causing a selected typewriter key to be quickly and easily operated for a selected predetermined number of strokes.

It is another object to provide an attachment for a typewriter which is adapted to cause a selected typewriter key to be quickly and easily operated for a selected predetermined number of strokes.

Further objects and advantages of this invention, as well as its construction, arrangement and operation will be apparent from the following description and claims in connection with the accompanying drawings, in which

Fig. 1 is a vertical section of the principal mechanism.

Fig. 2 is a sectional plan view of the principal mechanism.

Fig. 3 is a vertical cross section of the principal mechanism.

Fig. 4 is an end view of the entire machine.

Fig. 5 is an end elevation of the attachment of one of the machine's levers to a key lever of a typewriter by means of a link.

Fig. 6 is a side elevation of the attachment of one of the machine's levers to a key lever of a typewriter by means of a link.

Fig. 7 is a plan view of the attachment of the machine's lever link to a key lever of a typewriter.

Fig. 8 is a partial plan view of the machine's key starting device.

Fig. 9 is a partial side elevation of the machine's key starting device.

2

Fig. 10 is a partial sectional plan view of the brake device for stopping the machine and of the stroke timing mechanism.

Fig. 11 is a partial vertical section of the brake device for stopping the machine, the machine's key starting device, and of the stroke timing mechanism.

Fig. 12 is a partial vertical cross section of the brake device for stopping the machine; the machine's key starting device, and of the stroke time mechanism.

Fig. 13 is a plan view of the end support for the typewriter key operating shaft, indicating the typewriter key selector lever and showing a portion of the frame of a typewriter.

Fig. 14 is a side elevation of the end support for the typewriter key operating shaft, indicating the typewriter key selector lever and showing a section of the frame of a typewriter.

Fig. 15 is an elevation of the end support for the typewriter key operating shaft, indicating the typewriter key selector lever and showing a portion of the frame of a typewriter.

Fig. 16 is a partial end elevation of the principal mechanism indicating the method of securing the machine to a typewriter frame.

Fig. 17 is a partial vertical section at one end of the principal mechanism indicating the method of securing the machine to a typewriter frame.

The container 1 encloses and supports the mechanism of the prime mover. A movement downward of lever 2 turns shaft 3 rotating gear sector 4 upward against the tension of spring 5. The teeth of gear sector 4 receive those of pinion

6 which turns shaft 7 and ratchet gear 8 causing pawl 9, operated by spring 10, to be separated from ratchet gear 8. The prime mover is then ready for operation and can be started by pressing key 11 which forces lever 12 downward

against the force of spring 42 and pivoting about screw 15, releases pawls 13 and 14. Pressing key 11 also forces brake link 15 downward. The force exerted by spring 5 acting downward on gear sector 4 causes pinion 6 to turn shaft 7

which causes ratchet gear 8 to turn and exert pressure on pawl 9 which turns gear 16. The teeth on gear 16 engage those of pinion 17 on shaft 18 which turns gear 19 the teeth of which engage and turn pinion 20. Shaft 21 is turned

by pinion 20 which turns eccentric 22 thereby forcing link 23, which is attached thereto by screw 24, to oscillate vertically. Link 23 is attached to lever 25 by screw 22 and the vertical oscillation of link 23 causes a corresponding

oscillation of lever 25. Lever 25 is attached to

shaft 26. Levers 27 and 28 are attached to links 29 and 30 by pins 73. Links 29 and 30 are attached to keys of a typewriter. Shaft 26 is partly inserted into hollow shaft 32 which is free to rotate in the end support 33. The distance that shaft 26 can penetrate hollow shaft 32 will depend upon the width of a typewriter frame. Lever 31 is attached to link 34 which is attached to and moves securing ring 35. Sleeve 36, which has a hollow square inside, is moved along shaft 26 by securing ring 35 and is provided with teeth at each end arranged to engage the teeth of either lever 27 or 28. Shaft 26 thereby operates either lever 27 or 28, and the typewriter keys attached thereto depending upon the position of lever 31. Collars 37 and 38 secure levers 27 and 28 against endwise motion along shaft 26. End support 33 is provided with screws 39 and 40 for securing an adjustment of same to a typewriter frame.

Dial 43 is calibrated to indicate the number of strokes desired by a typewriter key, up to and including the total number of strokes permitted by the full travel of a typewriter carriage.

The number of strokes that it is desired to have made by a typewriter key is predetermined by turning dial 43 until the number desired is opposite to pointer 76.

To turn dial 43 it is necessary first to force it inward along shaft 60 toward the machine, against the pressure of spring 62, in order to disengage the slots on the outer edge of dial 43 from catch 61. Dial 43 is secured to shaft 60 by pin 63 which moves in a slotted hole along shaft 60. The turning of dial 43 to the starting position desired for timing the mechanism also turns shaft 60, and lever 44, which is attached thereto.

As pawls 13 and 14 are disengaged from gear 45 by lever 12 when the device is not operating, gear 45 is also turned by spring 46 with pin 47 in contact with lever 44.

When the whole mechanism is set in motion by pressure of key 11, the rotation of shaft 21 causes lever 48 to move upward and downward pivoting at pin 57, since shaft 21 is partly cut away to form a cam at the point of contact with lever 48. The upward motion of lever 48 is caused by the turning of shaft 21 to its full diameter. The downward motion of lever 48 occurs when shaft 21 has turned to a position permitting lever 48 to be forced downward by spring 49 into the partly removed portion of shaft 21. The motion of lever 48 is imparted to pawl 14 which is forced against gear 45 by spring 50 thereby turning gear 45 counterclockwise and moving pin 47 toward trigger 51 which is secured by screw 74. Pawl 13 also engages gear 45 by the pressure exerted by spring 52 and prevents gear 45 from rotating clockwise due to the force of spring 46, during the intervals when pawl 14 is disengaged from gear 45. Pin 47 on gear 45 continues to move counterclockwise away from the stationary lever 44, because of the motion imparted by pawl 14 until pin 47 strikes trigger 51 which releases key 11.

Since the turning of gear 45 because of the action of pawl 14 would otherwise move lever 44 with it because of the tension in spring 46, it is necessary that shaft 60 to which lever 44 is attached may be restrained from turning. This is accomplished by the locking of dial 43 to catch 61 which engages in slots on the outer edge of dial 43. The releasing of key 11 permits spring 53 to force brake link 15 upward which moves

brake band 54 into contact with brake drum 55 thereby causing the entire mechanism to stop working. An adjusting screw 56 is provided to move pin 57 which forces lever 48 toward or away from shaft 21. An inclined slotted hole is provided in lever 48 at the cam of shaft 21 and the turning of screw 56 forces lever 48 into a higher or lower position to obtain the exact timing position required for pawl 14, when engaging the teeth of gear 45.

In event that the operator decides to stop the machine before it has run the total number of strokes of the typewriter key, as determined by the setting of dial 43, a key 58 is provided which when pressed downward will trip trigger 51 against the force of spring 59 thereby releasing key 11 which will stop the mechanism from running, and timing gear 45 will be released by pawls 13 and 14 and return pin 47 to the starting position against lever 44. Releasing of pressure on key 58 permits trigger 51 to return to its normal position due to the upward force exerted by spring 59.

The inner bearing of shaft 18 is supported by column 64 and the bearings of shaft 21 and the inner bearing of shaft 60 are supported by hanger 65 and bracket 66.

Bracket 67 is provided to support lever 12, pawl 13, spring 53 and the shaft of key 11. Bracket 68 provides connections for pin 57, brake band pin 69 and spring 49.

Clips 41 secure the principal mechanism to a typewriter frame by means of screws 70 through clips 71, which are attached to container 1.

The apparatus according to this invention does not interfere with the normal operation of the typewriter. For example, the repeating apparatus that forms a part of this invention can be constantly left in an inoperative or "unset" condition in which each key operates for a single stroke in the usual manner.

As previously set forth the apparatus according to this invention may comprise an integral part of the typewriter as it leaves the manufacturer, or alternatively, it may comprise an attachment which is placed on any typewriter after its completion. Numerous structural adaptations necessary to permit the use of an attachment according to this invention on special types of typewriters will obviously be within the ability of those skilled in the art.

Changes can be made in this invention without departing from the spirit and scope thereof as set forth in the appended claims.

The invention described herein may be manufactured and used by or for the Government of the United States of America for governmental purposes without the payment of any royalties thereon or therefor.

What is claimed is:

1. In a typewriter an attachment for causing repeated actuation of at least one selected typewriter key, said attachment comprising a motor, a driven shaft rotated by said motor, an actuating shaft, linkage interconnecting said driven and actuating shafts so that rotation of said driven shaft will cause oscillation of said actuating shaft, linkage from said actuating shaft to at least one typewriter key, a clutch on said actuating shaft for selectively engaging the actuating shaft with the linkage to at least one typewriter key to cause repeated actuation of the key upon oscillation of the actuating shaft, a brake that is operative to restrain said driven shaft to prevent oscillation of said actuating shaft, resilient means

for urging said brake into operative position, a trigger that is operative for retaining the brake in inoperative position so that said driven shaft may rotate and cause oscillation of said actuating shaft, resilient means for urging said trigger into operative position, a ratchet wheel mounted adjacent said trigger for rotation with respect to said trigger, a lever adjacent said ratchet wheel, means for oscillating said lever upon rotation of said driven shaft, a ratchet mounted on said lever for engagement with said ratchet wheel so that rotation of said driven shaft and oscillation of said lever will cause said ratchet to rotate said ratchet wheel through an angle proportional to the angle of rotation of said driven shaft and the number of oscillations of said actuating shaft, a pin on said ratchet wheel mounted for engagement with said trigger, and means for rotating the ratchet wheel to withdraw said pin from said trigger through an angle proportional to a predetermined number of oscillations of said actuating shaft so that upon oscillation of said actuating shaft the predetermined number of times said wheel will be rotated through the angle of withdrawal to cause said pin to upset said trigger so that said brake operates to arrest the driven shaft and prevent further oscillation of said actuating shaft.

2. In a machine having a part adapted for repeated actuation, an attachment comprising a motor, a driven element coupled to said motor for actuation at all times when said motor operates, means connecting said driven element and the part to cause repeated actuation of the part by said driven element, means operative to lock said driven element against actuation, means coupled to said driven element and operative after a predetermined degree of actuation of said driven element to actuate said locking means to lock said driven element and motor against actuation, and manual control means for selectively actuating said locking means at the discretion of an operator.

3. In a machine having a part adapted for repeated actuation, an attachment comprising a motor, a driven shaft coupled to said motor for rotation at all times when said motor operates, means connecting said driven shaft and the part to cause repeated actuation of the part by said driven shaft, means operative to lock said driven shaft against rotation, means coupled to said driven shaft and operative after a predetermined rotation of said driven shaft to actuate said locking means to lock said driven shaft and motor against actuation, and manual control means for selectively actuating said locking means at the discretion of an operator.

4. In a machine having a part adapted for repeated actuation, an attachment comprising a motor, a driven shaft coupled to said motor for rotation at all times when said motor operates, means connecting said driven shaft and the part to cause repeated actuation of the part by said driven shaft, a brake operative to restrain said driven shaft against rotation, a trigger for retaining said brake in inoperative position to permit rotation of said driven shaft, means coupled to said driven shaft and operative after a predetermined rotation of said driven shaft to upset said trigger so that said brake operates to lock said driven shaft and motor against operation, and manual control means for selectively upsetting said trigger at the discretion of an operator.

5. In a machine having a part adapted for re-

peated actuation, an attachment comprising a motor; a driven shaft coupled to said motor for rotation thereby; means connecting said driven shaft and the part to cause repeated actuation of the part by said driven shaft; a brake operative to restrain said driven shaft against rotation; a trigger for retaining said brake in inoperative position to permit rotation of said driven shaft; and means for upsetting said trigger including a second shaft adapted to be fixed in a selected position, a ratchet wheel freely rotatable on said second shaft, an arm fixed to said second shaft for rotation therewith, a pin fixedly mounted on said wheel and adapted to contact said arm, spring means for urging said wheel into position with said pin in contact with said arm, and a pawl actuated by said driven shaft for rotating said ratchet wheel to withdraw said pin from said arm, said trigger being disposed in the path of movement of said pin.

6. In a machine a driven shaft; a brake operative to restrain said driven shaft against rotation; a trigger for retaining said brake in inoperative position; and means for upsetting said trigger including a second shaft adapted to be fixed in a selected position, a wheel freely rotatable on said second shaft, an arm fixed to said shaft for rotation therewith, a pin fixedly mounted on said wheel and adapted to contact said arm, spring means for urging said wheel into position with said pin in contact with said arm, and means coupling said wheel to said driven shaft for rotation therewith to withdraw said pin from said arm, said trigger being disposed in the path of movement of said pin.

7. In a machine having a part adapted for repeated actuation, an attachment comprising a motor, a driven element coupled to said motor for actuation at all times when said motor operates, means connecting said driven element and the part to cause repeated actuation of the part by said driven element, means operative to lock said driven element against actuation, and means coupled to said driven element and operative after a predetermined degree of actuation of said driven element to actuate said locking means to lock said driven element and motor against actuation, said last means including index means adapted to be manually set by an operator in a position corresponding to said predetermined degree of actuation, said index means remaining fixed during said predetermined degree of actuation so that repetition of the predetermined degree of actuation can be effected without resetting said index means.
